UNITED STATES PATENT OFFICE

ERNEST BLASBERG, OF HERNDON, PENNSYLVANIA

ADJUSTABLE MILL NUT

Application filed May 7, 1931. Serial No. 535,793.

This invention relates to an adjustable threadless mill nut, to be used for spinning or throwing machines, in connection with a spindle and a bobbin, and adapted to hold a 5 flyer at any desired level on the spindle above the bobbin.

The purpose of the invention is to provide a means for adjusting the nut to the changing position which the bobbin takes on the 10 spindle, due to wear, and also to provide a nut to fit spindles which vary slightly in diameter.

As at present constructed and used, the keeper is made of one solid piece of wood with 15 a hole through the center, which is usually placed on top of the spindle to prevent the flyer from working upward and breaking the thread. It is often found necessary to have the bore in this keeper enlarged or made 20 smaller, to fit different sized spindles, and this must be done by the user. Another disadvantage of the device now in use is that when the bobbin after usage moves downward on the spindle, there is too much upward play 25 of the flyer, causing frequent breakage of the thread. My invention is designed to overcome these faults.

In the accompanying drawings:

Figure 1 is a perspective view of a spindle, 30 on which are shown a bobbin, a flyer and an adjustable nut.

Figure 2 is a top plan view of the adjustable nut, showing the retaining spring in the bore.

Figure 3 is a view of the nut with the upper half removed to show the spring and the means for securing the spring to the nut.

Figure 4 is a perspective view of the nut.

Referring to the drawings, *a* indicates a 40 spindle socket of a spinning or throwing machine, *b* is a spindle secured therein, *c* is a bobbin placed on the spindle, *d* is a flyer on the spindle adjacent to the top of the bobbin and prevented from changing its level by the 45 adjustable nut *e* which may be held securely in all positions.

The adjustable nut *e* has an axial bore *f* and a narrow and relatively deep groove *g* extending from its periphery inward close 50 to the bore *f*, the wall between said groove

and bore being cut away at one side of the axis of the bore. *h* indicates a resilient spring, which is of wire in the present construction, inserted in the groove *g*. The center of the curved portion, marked *i*, of said 55 spring extends slightly into the bore. The looped members *j* of the spring pass around the anchor pins *k* which are slightly out of diameter of the nut. The free ends *l* of the spring lie within the groove. 60

The manner in which the nut operates is as follows:

When the nut is placed on the top of the spindle, it is automatically adjusted to fit the spindle, by means of the resilient spring 65 in the bore. The nut will stay tight on the upper end of the spindle but it can easily be pushed down on it if the low position of a different bobbin on the same spindle necessitates it, the wire being simply pushed into 70 the groove. When the curved portion of the spring is forced back into the groove, the free ends extend outwardly. Lifting the nut to the upper end of the spindle will cause the wire—due to its elasticity—to go back to its 75 original position.

Having described my invention, what I claim as new and desire to secure by Letters Patent is:

A threadless nut comprising a body having 80 an axial bore to receive a spindle and having a narrow relatively deep groove extending from its periphery inward close to said bore, the wall between said groove and bore being cut away at one side of the axis 85 of the bore, anchoring pins in said body extending across the groove at opposite sides of the bore and a resilient wire extending through the cut-away part of said wall and looped around the anchoring pins, the free 90 ends of the wire lying within the groove.

In testimony whereof I hereunto affix my signature.

ERNEST BLASBERG.
